ATTORNEYS

UNITED STATES PATENT OFFICE.

CLEN S. HUMPHREY, OF BROOKLYN, NEW YORK.

BOX AND COVER.

Application filed December 3, 1923. Serial No. 678,260.

To all whom it may concern:

Be it known that I, CLEN S. HUMPHREY, a citizen of the United States, and a resident of the city of New York, borough of Brooklyn, in the county of Kings and State of New York, have invented a new and Improved Box and Cover; of which the following is a full, clear, and exact description.

This invention relates to boxes and pertains particularly to an improved means of connection between the body and cover of the box. The invention is particularly applicable to boxes for containing cigars or other similar articles of merchandise which are displayed for sale in the original box or package, and the same contemplates as an object a means of connection between the cover and box which permits of the swinging of the cover respectively to a rearwardly inclined display position, to a vertically disposed display position with the lower edge of the cover in contact with the box supporting surface, or to a position for supporting the box body in a rearwardly inclined display position.

As a further object the invention aims to provide a box body and cover having a connection of the character set forth, which is extremely simple in its construction and operation, which is inexpensive to manufacture and produce, and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a perspective view of a box constructed in accordance with the invention, and illustrating the same with the cover in closed position.

Fig. 2 is a similar view with the cover in its rearwardly inclined display position.

Fig. 3 is a similar view with the cover in its vertical display position.

Fig. 4 is a similar view with the cover employed as a means for supporting the box body in rearwardly inclined display position.

Referring to the drawings by characters of reference, 10 designates the box body, 11 the cover therefor, the former being provided with outwardly projecting rivets 12 from the upper rear corners of its side wall 13, which rivets constitute trunnions. The cover 11 is provided with depending side flanges 14 which are designed when the cover is closed to fit over the upper ends of the outer side walls 13 of the box body. The flanges 14 are provided with longitudinally extending slots 15 having offset terminals 16 and 17. The rivets or trunnions 12 project through the slots 15 to constitute a means of connection between the cover and the box body to allow for relative sliding and swinging movement of the cover with respect to the body.

When the cover is in closed relation, as illustrated in Fig. 1, the trunnions or rivets 12 are positioned in the rear ends of the slots 15. When it is desired to arrange the cover 11 in the rearwardly inclined display position as illustrated in Fig. 2, the cover is swung to an open position and the offset terminals 17 are engaged with the trunnions or rivets 12, while the rear edge 18 of the cover engages with the rear wall 19 of the box body which limits rearward inclined swinging movement of the cover and maintains the same in its inclined display position. When it is desired to dispose the cover in a vertical display position at the rear of the box body as illustrated in Fig. 3, the cover is swung from a closed position upward to a vertical position and then is slid downwardly until its rear edge contacts with the supporting surface for the box body. In this position the rivets or trunnions 12 are disposed intermediate the ends of the slot 15. When it is desired to employ the cover as a means for supporting and maintaining the box body in a rearwardly inclined display position as illustrated in Fig. 4 the cover is slid a further distance downwardly than the position illustrated in Fig. 3 and the rivets 12 are positioned within the offset terminals 16 at the forward ends of the slots 15. This disposes the rear edge 18 of the cover 11 an appropriate distance below the bottom of the box body to give the required rearward inclination thereto and that the box is supported from the front lower edge of the body and the rear or lower edge of the cover when in this position.

From the foregoing it will thus be seen that a box having a connection between its

cover and body is provided which affords means for variously displaying the contents of the advertising matter on the inside of the cover, which is especially designed for 5 cigar boxes or the like.

I claim:

1. A box including a body and a cover, and a means of connection therebetween to permit of the swinging of the cover selectively to a rearwardly inclined display position relative to the body with the body disposed in flat contact with its supporting surface; to a vertically disposed display position with the rear end of the cover in contact with the box supporting surface and with the body in flat contact with said supporting surface; and to a position for supporting the body of the box in a rearwardly inclined display position with respect to the supporting surface.
2. A box including a body and a cover, and interengaging means of connection therebetween to permit of relative sliding and swinging movements of the cover with respect to the body, whereby the cover may be maintained by said means at a rearwardly inclined display position relative to the body with said body in flat contact with its supporting surface, or maintained in a position in contact with the rear wall of the body and extending below the bottom thereof to support said body in a rearwardly inclined display position with respect to its supporting surface.
3. A box body and cover having interengaging means of connection therebetween

whereby to permit the cover to be selectively arranged in covering position on the body, in a rear upwardly inclined display position from the upper rear edge of the 40 body, in a vertical display position against the rear wall of the body with the rear edge of said cover supported by the box body supporting surface, and in a position against the rear wall of the body and projecting below the bottom of the body whereby to support the said box body in a rear upwardly inclined display position with respect to its supporting surface.

4. A box body and cover having inter- 50 engaging means of connection therebetween whereby to permit the cover to be respectively arranged in covering position on the body, in a rear upwardly inclined display position from the upper rear edge of the 55 body, in a vertical display position against the rear wall of the body with the rear edge of said cover supported by the box body supporting surface, and in a position against the rear wall of the body and projecting below the bottom of the body whereby to support the said box body in a rear upwardly inclined display position, said means of connection comprising trunnions projecting outwardly from the upper rear corners of the 60 side walls of the box body, and depending side flanges on the cover having longitudinal slots formed with offset terminals at its opposite ends and engaging said trunnions.

CLEN S. HUMPHREY.
